UNITED STATES PATENT OFFICE.

CHARLES T. HATCH, OF ALBION, MICHIGAN, ASSIGNOR TO UNION STEEL PRODUCTS COMPANY, OF ALBION, MICHIGAN.

POULTRY COOP OR CRATE.

Application filed August 24, 1928. Serial No. 301,713.

The main objects of this invention are to provide an improved poultry coop or crate in which the parts are simple and economical and easily assembled and at the same time 5 when assembled provides a strong and rigid structure.

Objects relating to details and economies of my invention will appear from the description to follow. The invention is 10 defined and pointed out in the claims.

A structure which is a preferred embodiment of my invention is illustrated in the accompanying drawing, in which:

Fig. 1 is a fragmentary side view of a 15 poultry coop or crate of the feeding battery type embodying the features of my invention.

Fig. 2 is a perspective view of one of the 20 wall units.

Fig. 3 is an enlarged fragmentary perspective view showing details of the mounting of the wall units.

Fig. 4 is an enlarged detail view partially in section on line 4—4 of Fig. 1.

Fig. 5 is an enlarged detail section on line 25 5—5 of Fig. 1.

In the drawing similar reference characters refer to similar parts throughout the several views.

Referring to the drawing, I provide a 30 frame comprising corner uprights 1 of angled cross section and intermediate uprights 2. The horizontal top and bottom side members 3 and 4 are connected to the corner up-

rights by the corner irons 5. The intermediate uprights 2 are connected at their upper and lower ends to the top and bottom horizontal members. I have not illustrated the end structure as that does not appear necessary to an understanding of my invention.

The structure illustrated has a vertical series of compartments as the usual foraminated compartment floors 6 supported by the ledges 7 arranged in opposed pairs on the 45 corner and intermediate uprights, these ledges being formed of channel iron facing inwardly, the floors 6 resting upon the ledges, the edges of the pans 8 being engaged between the arms of the channel iron

ledges, as illustrated in the drawing. 50

The wall units are formed of vertical bars or rods 9, the horizontal bars 10 being arranged in pairs, the pairs of bars being spaced relative to each other to provide openings 11 in the wall unit through which the floors and pans may be introduced and removed. 55

The doors 12 illustrated are of the type illustrated in the patent to Dean No. 1,522, 60 87 dated January 13, 1925.

On the intermediate uprights I mount a plurality of U-shaped wall unit supports 13, these being secured in position by the rivets 14 so that the arms 15 of the supports project outwardly. These arms are offset so that the vertical bars 9 of the wall units may be arranged between them, as shown in Figs. 3 and 4, with the horizontal bars 10 of the wall units engaged in notch-like recesses 16 in the upper edges of the arms. 65

The corner uprights are provided with eye bolts 17 with which the lower ends of the outer vertical bars of the wall units are engaged and also with hooked bolts 18 clamping these outer bars to the corner uprights thereby effectively securing the parts in assembled relation; at the same time, the parts may be quickly assembled or disassembled should occasion require. 70

I have illustrated and described my improvements in an embodiment which I have found very satisfactory.

Having thus described my invention, what I claim as new and desire to secure by Letters Patent, is:

1. In a structure of the class described, the combination of a frame comprising corner and intermediate uprights, compartment bottom and pan supporting ledges mounted on said corner and intermediate uprights in opposed pairs, U-shaped wall unit supports arranged to embrace the intermediate uprights with their arms projecting outwardly therefrom, the upper edges of the projecting portions of said arms being notched, eye bolts on said corner uprights adjacent their lower ends, wall units comprising vertical side bars and coacting pairs of horizontal bars, there being a space between the coacting pairs of horizontal bars 90

permitting the insertion and removal of the parts supported by said ledges, vertical slats secured to said coacting pairs of horizontal bars, said wall units being arranged with 5 the lower ends of their outer vertical bars engaged in said eye bolts and with certain of their horizontal bars in engagement with said notches in said supports with their inner vertical bars between the arms of said supports, and hooked clamping bolts on said corner uprights engaging the outer vertical bars.

2. In a structure of the class described, the combination of a frame comprising corner 15 and intermediate uprights, compartment bottom and pan supporting ledges mounted on said corner and intermediate uprights in opposed pairs, U-shaped wall unit supports arranged to embrace the intermediate up- 20 rights with their arms projecting outwardly therefrom, the upper edges of the projecting portions of said arms being notched, wall units comprising vertical side bars and coacting pairs of horizontal bars, there being 25 a space between the coacting pairs of horizontal bars permitting the insertion and removal of the parts supported by said ledges, vertical slats secured to said coacting pairs of horizontal bars, said wall units being ar- 30 ranged with certain of their horizontal bars in engagement with said notches in said supports with their inner vertical bars be- 35 tween the arms of said supports, and clamping bolts on said corner uprights engaging the outer vertical bars.

3. In a structure of the class described, the combination of a frame comprising corner and an intermediate upright, U-shaped wall supports embracing said intermediate up- 40 right with their arms projecting outwardly therefrom, the projecting portions of said arms having upwardly facing recesses therein, eye bolts on said corner uprights adjacent their lower ends, wall units comprising vertical side bars and horizontal bars, vertical slats secured to said horizontal bars, said wall units being arranged with the lower ends of the outer vertical bars en- 45 gaged in said eye bolts and with certain of their horizontal bars in engagement with said recesses in said supports and with their vertical bars between the arms of said sup- 50 ports, and hooked bolts on said corner up- rights engaging the outer vertical bars.

5. In a structure of the class described, the combination of a frame comprising corner and an intermediate upright, U- 55 shaped wall supports embracing said intermediate upright with their arms projecting outwardly therefrom, the projecting portions of said arms having upwardly facing recesses therein, wall units comprising vertical side bars and horizontal bars, vertical slats secured to said horizontal bars, said 60 wall units being arranged with certain of

their horizontal bars in engagement with said recesses in said supports and with their vertical bars between the arms of said supports, and hooked bolts on said corner up- 70 rights engaging the outer vertical bars.

5. In a structure of the class described, the combination of a frame comprising corner and an intermediate upright, U-shaped wall supports embracing said intermediate upright with their arms projecting outwardly there- 75 from, the projecting portions of said arms having upwardly facing recesses therein, wall units comprising vertical side bars and horizontal bars, vertical slats secured to said horizontal bars, said wall units being ar- 80 ranged with the horizontal bars in engage- 85 ment with said recesses in said supports, and means for releasably securing the outer vertical bars to said corner uprights.

6. In a structure of the class described, the combination of a frame comprising corner and an intermediate upright, pairs of hooked wall supporting arms projecting outwardly from said intermediate upright, wall 90 units comprising vertical and horizontal bars, certain of said horizontal bars being engaged with said supporting arms with the inner vertical bars between the arms, and wall panel securing bolts on the corner up- 95 rights.

7. In a structure of the class described, the combination of a frame comprising a pair of uprights, one of said frame up- 100 rights being provided with outwardly pro- jecting arms having upwardly facing re- cesses, compartment bottom and pan sup- 105 porting ledges mounted on said uprights in opposed pairs, a wall unit comprising ver- 110 tical side bars and coacting pairs of hori- 115 zontal bars with vertical slats secured to the coacting pairs of horizontal bars, there being a space between the coacting pairs of horizontal bars permitting the insertion and removal of parts supported by said ledges, the horizontal bars of said wall units being engaged with said recesses in said supports, an eye bolt on the other frame upright with which the lower end of the vertical bar of the wall unit is engaged, and hooked wall 120 unit clamping bolts on such frame upright.

8. In a structure of the class described, the combination of a frame comprising a pair of uprights, one of said frame uprights being provided with outwardly projecting arms having upwardly facing recesses, a wall unit comprising vertical side bars and coacting pairs of horizontal bars with vertical slats secured to the coacting pairs of horizontal bars, the horizontal bars of said wall units being engaged with said recesses in said supports, an eye bolt on the other frame upright with which the lower end of the vertical bar of the wall unit is en- 125 gaged, and hooked wall unit clamping bolts on such frame upright.

9. In a structure of the class described, the combination of a frame comprising a pair of uprights, one of said uprights being provided with an outwardly projecting arm 5 having an upwardly facing recess, compartment bottom and pan supporting ledges mounted on said uprights in opposed pairs, a wall unit comprising vertical side bars and coacting pairs of horizontal bars with vertical slats secured to the coacting pairs of horizontal bars, there being a space between the coacting pairs of horizontal bars permitting the insertion and removal of parts supported by said ledges, the horizontal bars 10 of said wall units being engaged with said recesses in said supports, and clamping bolts for the wall unit carried by the other frame upright.

In witness whereof I have hereunto set my
20 hand.

CHARLES T. HATCH.
